RICHARD H. MARVIN, OF EAST LIVERPOOL, OHIO, ASSIGNOR TO THE R. THOMAS & SONS COMPANY, OF EAST LIVERPOOL, OHIO, A CORPORATION OF OHIO.

MULTIPLE-STRING INSULATOR SUSPENSION.

Application filed May 24, 1926. Serial No. 111,418.

My invention relates to multiple string insulator suspension units for electric power lines. The object of my invention is to provide a multiple string suspension unit in which the mechanical stresses are evenly divided between the several strings of the suspension unit.

In the accompanying drawings—

Fig. 1 is a side elevation of a suspension unit in which my invention is embodied in one form;

Fig. 2 is a similar view of a modification; and

Fig. 3 is a plan view of the latter.

With the increasing lengths of span between adjacent towers or poles employed for the support of the cables of electric power lines, the problem of providing insulator strings of mechanical strength adequate for the heavy mechanical stresses occasioned by the long spans, has become acute. Multiple strings arranged in parallel have been employed in some instances, but in order to distribute the stresses evenly between the several strings it has been necessary to employ strings of exact uniformity in over-all length. This is difficult to attain in practice by reason of variations both in insulators and in their fittings. To meet this situation, adjustable connections have been utilized, by which the length of the strings has been equalized. This not only involves the expense of adjustment, but is not satisfactory since dependable accuracy is not attained by the workmen, and, moreover, even after proper adjustment the take-up is apt to vary under service conditions, with resultant inequality of stresses on the several strings of the suspension unit.

My invention provides a suspension which insures exact distribution of stresses between the several strings regardless of the inescapable slight variations in length incident to manufacture. Moreover the layout is such that in case of failure of one of the strings, the stress is equalized between the remaining strings.

My invention may be embodied in structures which differ in detail while still accomplishing the same result in accordance with the principle which underlies my invention. The structures shown in the accompanying drawings are therefore to be regarded as merely illustrative of the invention.

In the form shown in Fig. 1 the suspension unit comprises a pair of hangers 15 and 16,

the hanger 15 having a link 17 for connection to the supporting tower (not shown) and the hanger 16 having a link 18 for connection to a cable clamp or the like (not shown). Uniting the hangers 15 and 16 is a group of insulator strings 19, eight in number, the several strings being identified by the references *a*, *b*, *c*, *d*, *e*, *f*, *g*, *h*. Balance levers 20, 21, 22, 23, 24, 25, 26 are centrally pivoted at *x* respectively on arms 27, 28, 29, 30, 31, 32, 33. Arms 28, 30 and 32 are carried by the hanger 15 and staggered with relation to the arms 27, 29, 31 and 33 carried by the hanger 16. Arms 34 and 35 at opposite ends of the hanger 15 support the upper ends of the terminal strings *a* and *h* of the series. Links 36 unite the several insulator strings at one end to the arms 34 and 35, or to the ends of the several balance levers 21, 23 and 25. Links 37 connect the opposite ends of the strings to the several balance levers 20, 22, 24 and 26.

By reason of the fact that the interconnection between adjacent strings is effected through the staggered balance levers 20—26, the arrangement affords in effect a flexible system such that by the working of the levers inequalities in string length are neutralized and the stresses of the load are distributed throughout the series of strings with absolute uniformity. Moreover, should one string fail, the portion of the load previously taken by this string is automatically apportioned between the remaining strings, so that the latter are placed under uniform stress at increased load. For example, should string *d* fail, the several balance levers 20—26 will tilt on their axes until the load is equalized between strings *a*, *b*, *c*, *e*, *f*, *g*, *h*, just as would be the case were string *d* initially of such length that levers 22—23 were tilted to their extreme limit of oscillation at the moment of load equalization. In the case of failure of string *d*, the suspension comprises not two dead ends 34—35, but four dead ends, viz., 22—34 for one group of strings *a*, *b*, *c*, and 23—35 for the other group of strings *e*, *f*, *g*, *h*. The load, instead of being taken by eight strings, is taken by seven, but the load is uniformly distributed on the several strings in both cases.

The construction shown in Fig. 1 would be impracticable in many situations by reason of its size. A much more compact arrangement is shown in Figs. 2 and 3, in which the same principle is involved. Here the hanger

members 38 and 39 respectively are in the form of four-armed brackets, the several arms 40 of the bracket 38 being staggered with respect to the arms 41 of the bracket 39. 5 Preferably each arm is provided with a clevis 42 lying in a plane at right angles to the plane of the arm and adapted to receive a pivot pin 43 upon which is pivoted a rock lever 44. To the ends of the rock levers the 10 insulator strings are connected after the same fashion as in the construction first described and with the same effect. In this layout one of the rocker arms is held against oscillation by stops S to maintain all of the 15 arms in planes substantially normal to the strain axis of the suspension. The several levers are arranged at an angle to each other in staggered sequence, and are symmetrically arranged around the axis of suspension. 20 In effect the arrangement of Figs. 2 and 3 is equivalent to the bending of the hangers 15 and 16 of Fig. 1 into circular form; the cross arm brackets afford merely a more expedient manufacturing proposition. 25 Various modifications of details of construction and arrangement of parts will readily occur to those dealing with the problem without departing from what I claim as my invention. 30 I claim— 1. A multiple string suspension insulator unit comprising a pair of spaced hangers, a series of balance levers pivoted on the respective hangers, the axes of the levers on one hanger being staggered with respect to the axes of the levers on the other hanger, in combination with a series of insulator strings connecting said hangers, adjacent strings being connected at one end to the opposite ends of a lever pivoted on one hanger, while the other ends of said strings are connected to adjacent levers pivoted on the other hanger, to afford a flexible interconnection between the several strings operative to even- 40 ly distribute between the said strings the me-

chanical stresses imposed upon the group. 2. A multiple string suspension insulator unit comprising a pair of spaced hangers, a series of balance levers pivoted on the respective hangers and arranged at an angle to each other in staggered sequence, in combination with a series of insulator strings connecting said hangers, adjacent strings being connected at one end to the opposite ends of a lever pivoted on one hanger, while the other ends of said strings are connected to adjacent levers pivoted on the other hanger, to afford a flexible interconnection between the several strings operative to evenly distribute between the said strings the mechanical stresses imposed upon the group. 50

3. A multiple string suspension insulator unit comprising a pair of spaced hangers, a series of balance levers pivoted on the respective hangers and arranged at an angle to each other in staggered sequence and symmetrically around the axis of suspension, in combination with a series of insulator strings connecting said hangers, adjacent strings being connected at one end to the opposite ends of a lever pivoted on one hanger, while the other ends of said strings are connected to adjacent levers pivoted on the other hanger, to afford a flexible interconnection between the several strings operative to evenly distribute between the said strings the mechanical stresses imposed upon the group. 60

4. A multiple string suspension insulator unit comprising a pair of multi-arm hanger members having a common suspension axis, the arms of the respective hanger members being staggered with relation to each other, together with balance levers carried by said arms and insulator strings extending between the balance levers of the respective hanger members and interconnecting the levers in sequence. 80

In testimony whereof I have signed my name to this specification.

RICHARD H. MARVIN.
